[57] CLAIM

The ornamental design for a combined telephone handset and base therefor, substantially as shown and described.

DESCRIPTION

FIG. 1 is a top plan view of a combined telephone handset and base therefor showing my new design;

FIG. 2 is a front elevation thereof;

FIG. 3 is a right side elevation thereof, the undisclosed

left side is a mirror image of the side shown;

FIG. 4 is a rear elevation thereof; and

FIG. 5 is a bottom plan view thereof.

FIG. 1

FIG. 2

FIG. 3

FIG. 4

FIG. 5
